United States Patent Office.

JOHN RINGEN, OF ST. LOUIS, MISSOURI.

Letters Patent No. 86,250, dated January 26, 1869.

IMPROVED WASHING-MACHINE.

The Schedule referred to in these Letters Patent and making part of the same.

To all whom it may concern:

Be it known that I, JOHN RINGEN, of St. Louis, in the county of St. Louis, and State of Missouri, have invented a new and improved Washing-Machine; and I do hereby declare that the following is a full, clear, and exact description thereof, which will enable others skilled in the art to make and use the same, reference being had to the accompanying drawings, forming part of this specification, in which—

Figure 1 is a vertical longitudinal section of my improved machine, taken through the line $x x$, fig. 2.

Figure 2 is a top or plan view of the same.

Similar letters of reference indicate corresponding parts.

My invention has for its object to furnish an improved washing-machine, simple in construction, easily operated, and effective in operation, which will do its work quickly and thoroughly, turning the clothes, pressing and rubbing them, and without the least injury even to the most delicate fabrics, and

It consists in imparting a rubbing as well as a pounding-motion to the dash-board, by means of a resting-point or fulcrum between the crank and board, as will be hereinafter more fully described.

A is the box or tub of the machine, which is made rectangular in form, is supported upon legs B, of such a length as to raise the tub to a convenient height, and is provided with a close cover, C, to prevent the water or suds from spattering out, when the machine is being used.

To the inner surface of one end of the box A is secured a stationary rubbing-board, D, which may be grooved or perforated, or both, and against which the clothes are pressed and rubbed by the action of the movable rubbing-board E, which is made in two parts, e^1 and e^2 , which are hinged to each other at their upper edges, and the lower parts of which are kept apart by coiled springs, e^3 , placed between them, as shown in fig. 1.

This construction holds the lower part of the part e^1 forward, and, at the same time, makes the said rubber elastic.

The forward surface of the part e^1 is grooved or corrugated, as shown in fig. 1.

The part e^2 , of the rubbing-board E, near its upper edge, is rigidly and securely attached to the forward

ends of the two bars F, which pass back through vertical slots in the rear end-board of the tub, or box A, and their rear ends are pivoted to the shaft G, where they are connected together, and held in their proper relative positions by the bar or round, H, which also serves as a handle for operating the machine.

The shaft G, near its ends, is bent twice at right angles, to form a double crank, and is pivoted to the outer ends of the bars I, the inner ends of which are rigidly and securely attached to the end of the box A.

To each end of the shaft G is attached a balance-wheel, J, to give steadiness to the movement of the machine.

In the lower ends of the slots, in the end of the tub A in which the bars F work, are placed friction-rollers, K, to diminish the friction in operating the said bars.

L are cups or spouts, attached to the outer side of the end of the box A, at the lower end of the slots in said end, to receive any water or suds that may spatter through said slots, and guide it back into the tub.

In using the machine, the clothes to be washed are placed in the space between the stationary rubbing-board D and the movable flexible rubbing-board E, and as the machine is operated, the peculiar arrangement of the operating-parts of the said machine causes the movable rubber E to press and rub the clothes against the stationary rubber D, and, at the same time, to turn or revolve the said clothes, so that a new part of said clothes may be operated upon at each movement of the machine, each point of said movable rubber describing a pear-shaped figure, as shown in dotted red lines in fig. 1.

I am aware that machines have been constructed wherein a yielding pounder has been forced against the wash-board by means of a crank and shaft, and therefore I do not claim these; but

What I do claim, is—

The crank G and shaft F, when supported at the point K, and carrying the dasher E, substantially as and for the purpose described.

JOHN RINGEN.
